FRED E. NORTON, OF WORCESTER, MASSACHUSETTS, ASSIGNOR TO GENERAL ELECTRIC COMPANY, A CORPORATION OF NEW YORK.

GOVERNING MECHANISM FOR TURBINES.

1,188,197.

Specification of Letters Patent. Patented June 20, 1916.

Application filed May 9, 1913. Serial No. 766,575.

To all whom it may concern:

Be it known that I, FRED E. NORTON, a citizen of the United States, residing at Worcester, in the county of Worcester and State of Massachusetts, have invented certain new and useful Improvements in Governing Mechanism for Turbines, of which the following is a specification.

The common practice of today with turbine builders is to provide each turbine with a speed governor driven by its rotor and to utilize this governor to control the opening and closing of an admission valve means as the load changes. Such an arrangement gives a speed range of say three to four per cent. from no load to full load. Often the limits of the speed range are fixed once for all but in some cases adjusting means are provided for changing the tension of the governor spring so that the range of speed of the turbine is a little higher or a little lower as occasion requires. Such adjusting means are commonly known as synchronizing devices. For many purposes, notably where the turbines drive electric generators, this arrangement is satisfactory, but for other purposes, notably where the turbines drive centrifugal compressors for blast furnaces and gas generators, which compressors are called on to deliver widely differing amounts of air under varying pressures, it is insufficient or defective. In blast furnace and gas generator work particularly the conditions change very greatly from time to time according to the amount and character of the ore in the furnace and to the amount of gas taken from the generator. Briefly stated, the principal distinction between turbine driven electric generators and turbine driven air compressors is that the former operate as constant speed units and the latter as variable speed units.

My invention has for its object to overcome the objections above stated and to provide an improved governing mechanism which is capable of effectively controlling the turbine over a wide range of speed as the work required thereof varies.

Briefly stated, my improved governing mechanism comprises a regulator admitting elastic fluid to the turbine subject to the control of a speed governor for what may conveniently be termed the normal operating conditions. In addition to this a secondary or variable speed governor is pro-

vided that is also responsive to speed changes of the turbine and which is put into service when the speed is to be maintained below normal. This acts on said regulator either directly, or indirectly through some intermediary, such as the pilot valve of the motor which adjusts the regulator with respect to its seat or seats. This secondary or variable speed governor may with advantage take the form of a movable member which is acted upon by fluid from a pump driven by the turbine. This governor can readily be adjusted to meet new speed conditions by changing the tension of a spring which opposes said member, by passing a part of the fluid from the pump, or by adjusting both the spring and the bypass.

In the accompanying drawing which illustrates one of the embodiments of my invention, Figure 1 is a somewhat diagrammatic view illustrating my improved governor mechanism; Fig. 2 is a view of the needle valve and its casing; Fig. 3 is a sectional view of a fluid retarding device; and Fig. 4 is a plan view of a turbine driven compressor showing the regulating mechanism in position.

10 indicates a turbine of any suitable construction having a suitable speed responsive device 11 comprising the usual weights and an opposing spring. This primary governor controls the opening and closing of a valve means or regulator 12 through a system of levers. Driven by the turbine is a compressor or equivalent apparatus 13 whose load is liable to change over a wide range requiring different speeds of rotation. The governor is adapted for a speed regulation of about 2% over or under a predetermined speed and may for convenience be designated as a constant speed governor. Attached to a movable member of the governor is a lever 14, Fig. 1, to the free end of which is attached a link 15. To the lower end of the link is pivotally attached a floating lever 16 which is connected by a link 17 with the lever 18, the latter being connected to the pilot valve 19 and to the rod 20 of the motor 21 which actuates the valve means or regulator 12. The motor comprises a cylinder and a piston 22, the rod 20 of which is connected to the valve or valves admitting fluid to the turbine 10. As the load on the turbine changes a slight but

corresponding change in speed of the turbine takes place. This causes the governor lever 14 to change the position of the pilot valve 19, the latter to admit fluid under pressure to one side or the other of the piston 22 and thus admit more or less steam to the turbine. By connecting the lever 18 to the piston 20 the movement of the latter will restore the pilot valve to its initial position. This arrangement of the lever 18 forms what is commonly termed a follow-up device. The motor may be actuated by any suitable motive fluid, such for example as steam, water, oil or compressed air as desired.

The secondary or variable speed governor comprises a movable abutment or member, such for example as the siphon diaphragm 23. This diaphragm is connected to the rod 24 and its outward movement is opposed by a coiled extension spring 25, whose tension can be adjusted by the hand wheel 26, the latter being attached to a nut 27 that is threaded to the rod 24. The upper end of the spring is attached to a boss on the frame 28. To the lower end of the rod is attached a lever 29, the right-hand end of which is connected by the rod 30 with the floating lever 16. When the primary governor 11 is controlling the operation of the turbine the pin 31 connecting the rod 30 and the lever 16 acts as the fulcrum and is stationary, but when the secondary governor is in control the fulcrum 31 is adjusted up and down and the pin 32 becomes the fulcrum. The lever 29 may be pivotally supported by any suitable means. As shown it is mounted on the frame 28 which carries the diaphragm.

35 indicates a tank or casing at one end of the turbine and located therein is a gear pump 36 of ordinary construction for supplying fluid to the governor and lubricant to the bearings. On the upper end of the shaft 37 of the pump is a gear 38 that meshes with a worm 39 mounted on the end of the turbine shaft or otherwise driven thereby, so that as the speed of the turbine changes the speed of the pump will correspondingly change and in like manner. Fluid from the pump is discharged through the pipe or conduit 40 leading to the diaphragm 23 and through the pipe or conduit 41 to the bearings of the apparatus or to any other point that may be desired. The conduits 40 and 41 are arranged in multiple as regards the discharge of fluid from the pump for a purpose to be described later. At some suitable point in the conduit 41 is arranged a needle valve 42, best shown in Fig. 2, which controls the amount of fluid passing through the pipe 41 and hence the pressure in the pipe or conduit 40 leading to the diaphragm for a given speed of the turbine. Connected to the conduit 41 is a conduit 43 that leads back to the supply

tank 35 in which the gear pump is located. In this conduit 43 is located an adjustable relief valve 44 which may be set for any predetermined pressure and when that pressure is exceeded fluid is by-passed from the conduit 41 to the tank. As it is generally desirable to maintain a higher pressure in the conduit 41 than in the conduit 45 leading to the bearings, a perforated disk 47, Fig. 3, is interposed between them and at 75 a point beyond the conduit 43.

When the turbine is to be operated at constant speed within the limits of the speed governor 11 it acts through the lever 14 on the pilot valve of the motor in the ordinary manner increasing and decreasing the amount of steam admitted to the turbine by the regulator 12.

During the time that this primary governor is in service the secondary governor is inactive, the fluid pressure from the pump 36 distending the diaphragm 23 and causing its outer end to rest on the frame 28. This has the effect of fixing the position of the fulcrum 31. The lubricant delivered by the pump now passes from the conduit 41 partly to the bearings by the conduit 45 and the remainder through the conduit 43 and relief valve 44 back to the supply tank. The lubricant after passing through the bearings is also returned to the tank for further use.

Assuming now that the character of the load on the turbine, as determined by suitable indicators, is such that its speed to 100 attain the best results should be below the working range of the main or primary governor 11, which range as before stated is comparatively small, the secondary governor is put into service by the operator 100 and takes control, said primary governor remaining idle in so far as any controlling action is concerned. The secondary governor, however, acts on the regulator 12 through the larger part of the same mechanism that is connected to the primary governor thereby avoiding duplication of parts. This arrangement further has the advantage that the regulating mechanism is in constant use and hence the danger of some part failing 110 to work when required is reduced to a minimum.

Owing to the nature of the secondary governor it is capable of being widely adjusted by changing the tension of the 120 spring 25, and also by changing the opening of the needle valve 42. As an example of the requirements of air compressor service it is not uncommon to have to change the speed from 2,500 R. P. M. to 1,500 R. P. M. At times the compressor may, for example, be called on to deliver 40,000 cubic feet of free air per minute and at other times only 15,000 feet.

Assuming that the load conditions on the 120

turbine require it to operate at half its normal speed for example, which is far below the working range of the primary governor, the hand-wheel 26 is so adjusted as 5 to cause the spring 25 to oppose the necessary resistance to the outward movement of the diaphragm 23 to render it active and the valve 42 is set to properly restrict the passage of fluid to the conduit 41. Under 10 this condition the pump 36 may, as an example, be called upon to deliver fluid at 100 lbs. per square inch to balance the spring. As the speed changes up or down with load variations the lever 29 will raise 15 or lower the pivot 31 of the floating lever 16 and in so doing cause it to move about the fixed fulcrum 32 and adjust the pilot valve to admit more or less steam to the turbine, the action of the motor 21 and 20 regulator being the same as before but in a different speed range. The pivot 32 remains fixed under these conditions because the weights of the governor 11 are against their stops and for all practical purposes 25 the lever 14 is fixed.

As before stated, I prefer to use the pump 35 to supply lubricant to the bearings of the apparatus thereby utilizing it for a double purpose; *i. e.*, for governing and for 30 lubricating purposes. To prevent the flow of lubricant to the bearings from interfering with the proper action of the secondary governor by taking more fluid than they should, the adjustable needle valve 42 is 35 interposed in the conduit 41 beyond the conduit 40. This may, for example, be so adjusted that for a given speed of the turbine a pressure of 100 lbs. per square inch is maintained in the conduit 40 and dia- 40 phragm and a pressure of 35 lbs. in the conduit 41. It is important also to maintain an approximately constant bearing pressure so the relief valve is also set for 35 lbs. Before the lubricant can pass to 45 the bearings it has to flow through the relatively small perforation in the disk 47 and in so doing its pressure is further reduced, say to 30 lbs. per square inch for example, which remains substantially constant at all 50 times. The amount of fluid discharged by the pump is always sufficient to cause some fluid to flow through the relief valve, the amount being determined by the speed of the turbine and pump. But whether the 55 amount be small or large a substantially constant pressure is always maintained in the conduit 41 so that the diaphragm will quickly respond to any increase in pump pressure due to a change in speed of the 60 turbine. To state the matter in another way the pump delivers fluid to two conduits in multiple and in one of which a constant pressure is maintained as nearly as possible.

My improved governing mechanism has 65 the advantage of enabling the user to op-

erate the turbine at any speed that is necessary to meet the requirement of the service and this by a simple adjustment. It also permits the use without change of a simple and well-known type of speed governor of 70 relatively small size. Turbines in service can be readily adapted for varying speed conditions by the addition of the diaphragm and associated parts. Generally speaking, the only addition to the regulator 12 is the 75 floating lever 16 and link 15. Ordinarily the link 17 would be directly connected to the governor lever 14 instead of to the floating lever. As turbines are usually provided with gear pumps for lubricating purpose, 80 no change is required in this particular.

When the turbine is being controlled by the secondary governor the primary governor although not taking part in the normal regulation of the turbine stands ready 85 to do so in case of accident to the former. In other words the primary governor will prevent excess speed of the apparatus, without, however, shutting it down, when for any reason the operator makes an incorrect 90 adjustment of the secondary governor.

I have illustrated a siphon diaphragm as the secondary governor, but it is evident that other devices of an equivalent character can be employed. Care should of course be 95 exercised to select a device which is freely responsive to pressure changes and can be kept tight.

In accordance with the provisions of the patent statutes, I have described the principle of operation of my invention, together with the apparatus which I now consider to represent the best embodiment thereof; but I desire to have it understood that the apparatus shown is only illustrative and 10 that the invention can be carried out by other means.

What I claim as new and desire to secure by Letters Patent of the United States, is:

1. In combination, a motor, a regulator therefor, a governor which is responsive to the shaft speed of the motor and has a limited range of operation, a second governor which is also responsive to the shaft speed of the motor and has a different and wider range of operation, means connecting both of said governors to the regulator, and means enabling the regulator to be controlled by one governor to the exclusion of the other.

2. In combination, a prime mover, a regulator for varying the amount of energy admitted thereto, a motor for actuating the regulator, a pilot valve therefor, a primary governor which has a limited range of operation and is responsive to changes in the load of the prime mover for moving the pilot valve, a secondary governor that has a different and wider range of operation than the first, which is responsive to changes in

load on the prime mover and which also acts to move the pilot valve, and means enabling the regulator to be controlled by one governor to the exclusion of the other.

5. 3. In combination, a motor, a regulator therefor, a speed governor for controlling the regulator, a pump for creating a fluid pressure which varies with changes in speed of the motor, a member responsive to the fluid pressure that acts on the regulator, and a valve means for controlling the pressure exerted by the pump on the member.

4. In combination, a motor, a regulator for the motor, a speed governor for controlling the regulator, a pump for creating a fluid pressure which varies with changes in speed of the motor, a diaphragm which is sensitive to the pump pressure and acts on the regulator independently of the speed governor, a spring acting on the diaphragm in opposition to the pump pressure, and means for changing the tension of the spring.

5. In combination, a motor, a regulator for the motor, a speed governor for controlling the regulator, a second speed governor comprising a pump for creating a fluid pressure which varies with changes in speed of the motor, and a movable abutment sensitive to the pressure created by the pump; and means connecting the speed governor and the abutment to the regulator, so that said regulator may be controlled by either to the exclusion of the other.

6. In combination, a motor, a regulator for the motor, a speed governor for controlling the regulator, a second speed governor comprising a pump for creating a fluid pressure which varies with changes in speed of the motor, and a movable abutment sensitive to the pressure created by the pump; and a floating lever which is connected to the speed governor, to the abutment and to the regulator.

7. In combination, a motor, a regulator for the motor, a speed governor for controlling the regulator, a pump for creating a fluid pressure which varies with changes in speed of the motor, conduits connected in multiple relation to the pump, a device sensitive to the pressure created by the pump and located in one of the conduits, and means interposed in another of the conduits for maintaining a substantially constant pressure therein.

8. In combination, a motor, a regulator therefor, a speed governor for controlling the regulator, a pump for creating a fluid pressure which varies with changes in speed of the motor, said pump discharging fluid into multiple paths, a diaphragm and opposing spring acted upon by the fluid in one of the paths, an adjustable valve and a restricted orifice located in the other path, and a valve opening in response to pressure and interposed between the adjustable valve

and the restricted orifice for maintaining a substantially constant pressure in the second path.

9. In combination, a motor, a regulator for the motor, a pump for creating a fluid pressure which varies with change in speed of the motor, said pump discharging fluid to conduits arranged in multiple relation, a movable abutment interposed between the pump and the regulator, and means interposed in one of the conduits to maintain a substantially constant pressure therein.

10. In combination, a prime mover, a regulator for varying the amount of energy admitted thereto, a motor for actuating the regulator, a pilot valve therefor, a governor responsive to changes in load on the prime mover for moving the pilot valve, a secondary governor that has a different and wider range of operation than the first which also acts to move the pilot valve, and means for adjusting the secondary governor so that it will control the pilot valve when the speed of the prime mover is outside of the operative working range of the first-named governor.

11. In combination, a prime mover, a regulator for admitting motive fluid thereto, a primary and a secondary governor, a member that is connected to both governors and to the regulator, a fulcrum for the member which is fixed in position by the secondary governor when the primary governor is in operation, a second fulcrum for the member which is fixed in position by the primary governor when the secondary governor is in operation, and means for adjusting one of the governors so that the prime mover will have an operative speed that is outside of the range of control of the other governor.

12. In combination, a prime mover, a regulator for admitting motive fluid thereto, a primary speed governor, a secondary governor that is responsive to fluid pressure, a pump responsive to speed of the prime mover that supplies fluid to the secondary governor, a member for transmitting movements of both of the governors to the regulator, fulcrums for the member only one of which is active at a time, said fulcrums being positioned by the governors, and means for opposing a greater or less resistance to the action of the secondary governor to cause it to assume control of the regulator to the exclusion of the primary regulator.

13. In combination, a turbine, a regulator therefor, a governor comprising one element that is movable in response to pressure changes and acts to adjust the regulator, a pump driven by the turbine which supplies fluid under pressure to the governor and to a bearing of the turbine, conduits connected in multiple relation to the governor and the bearing, that to the governor

being unrestricted, and means for maintaining a substantially constant pressure in the conduit leading to the bearing.

14. In combination, a turbine, a regulator therefor, a motor for actuating the regulator, a pilot valve for the motor, and means responsive to the speed of the turbine for controlling the regulator, said means comprising a pump driven by the turbine, a 10 member sensitive to the pressure of the fluid

delivered by the pump, and means connecting the member with the pilot valve.

In witness whereof, I have hereunto set my hand this twenty-ninth day of April, 1913.

FRED E. NORTON.
